UNITED STATES PATENT OFFICE.

THOMAS W. DIXON, OF CHICAGO, ILLINOIS.

FUEL-VAPORIZER.

1,148,892.

Specification of Letters Patent.

Patented Aug. 3, 1915.

Original application filed December 8, 1914, Serial No. 876,111. Divided and this application filed February 23, 1915. Serial No. 10,002.

To all whom it may concern:

Be it known that I, THOMAS W. DIXON, a citizen of the United States, and a resident of the city of Chicago, county of Cook, and 5 State of Illinois, have invented certain new and useful Improvements in Fuel-Vaporizers, of which the following is a specification.

My invention relates to improvements in fuel vaporizers especially adapted for use on 10 explosive engines, the present application being a division of my prior application filed December 8, 1914, Serial No. 876,111.

The invention consists in the combinations and arrangements of parts hereinafter described and claimed.

The invention will be best understood by reference to the accompanying drawing which is a sectional view of a fuel vaporizer embodying my invention.

20 The preferred form of construction, as illustrated in the drawing, comprises a tubular casing 1 surrounding the exhaust pipe 2 of the engine and filled with finely divided metallic particles. One end of the casing 1 is connected by means of a fuel supply pipe 3 with a fuel supply tank 4, said tank 4 being in communication with a pressure tank 5 through a pipe 6 and pressure tank 5 being in communication with the exhaust 25 pipe through a pipe 7. A coil of pipe 8 is arranged around casing 1 with one end 9 thereof connected with the end of casing 1 opposite that into which pipe 3 leads. The other end of the coil 9 is connected by pipe 30 10 with the usual carbureter 11 of the engine.

By this arrangement, it will be observed that the fuel will be thoroughly heated and vaporized before passing to the engine, thus 40 increasing the efficiency of the engine.

While I have illustrated and described the preferred form of construction for carrying my invention into effect, this is capable of variation and modification without departing from the spirit of the invention. I, 45 therefore, do not wish to be limited to the precise details of construction set forth, but desire to avail myself of such variations and modifications as come within the scope of the appended claims.

50 I claim:

1. The combination with the exhaust pipe of an explosive engine, of a casing surrounding said pipe and filled with metallic particles; a coil surrounding said casing and 55 having one end connected therewith, the other end of said coil being in communication with the engine; and means for supplying fuel to said casing, substantially as described.

60 2. The combination with the exhaust pipe of an explosive engine, of a casing surrounding said pipe and filled with metallic particles; a coil surrounding said casing and having one end connected therewith, the 65 other end of said coil being in communication with the engine; a closed fuel tank also connected with said casing; a pressure tank connected with said exhaust pipe; and a connection between said pressure tank and 70 said fuel tank, substantially as described.

In testimony whereof I have signed my name to this specification in the presence of two subscribing witnesses.

THOMAS W. DIXON.
